(57) **CLAIM**

The ornamental design for a cutting tool, as shown and described.

DESCRIPTION

FIG. 1 is a front view of a cutting tool in accordance with Embodiment 1 of the present design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a first perspective view thereof;

FIG. 8 is a second perspective view thereof;

FIG. 9 is a cross sectional view taken along line 9-9 of FIG. 3;

FIG. 10 is a referential perspective view showing the state in use of the cutting tool attached to the holder by a fixing member, for cutting a rotating workpiece;

FIG. 11 is a front view of a cutting tool in accordance with Embodiment 2 of the present design;

FIG. 12 is a rear view thereof;

FIG. 13 is a top view thereof;

FIG. 14 is a bottom view thereof;

FIG. 15 is a right side view thereof;

FIG. 16 is a left side view thereof;

FIG. 17 is a first perspective view thereof;

FIG. 18 is a second perspective view thereof;

FIG. 19 is a cross sectional view taken along line 19-19 of FIG. 13; and,

FIG. 20 is a referential perspective view showing the state in use of the cutting tool attached to the holder by a fixing member, for cutting a rotating workpiece.

The broken lines in the referential perspective views represent unclaimed environmental subject matter.
